UNITED STATES PATENT OFFICE.

DANIEL ROUNDS, OF PORTLAND, MAINE.

REPAIR-LAST.

1,086,468.

Specification of Letters Patent. Patented Feb. 10, 1914.

Application filed September 12, 1912. Serial No. 719,902.

To all whom it may concern:

Be it known that I, DANIEL ROUNDS, a citizen of the United States, residing at Portland, in the county of Cumberland and State of Maine, have invented certain new and useful Improvements in Repair-Lasts, of which the following is a specification.

This invention relates to improvements in shoemakers' repair lasts and is designed to provide a simple laterally and longitudinally adjustable last.

In the drawings herewith accompanying and making a part of this application, Figure 1 is an elevation with a portion of the side removed of my improved last; Fig. 2 is a top plan with a portion of the top removed of the same; and Fig. 3 is a detail of the laterally expanding device.

In said drawings A is the heel part and B the toe part. Pivotaly mounted in the heel part is a block C provided with a longitudinal bar receiving opening D. Mounted in the toe part is a block E provided with a longitudinally extending bar receiving opening F. The block C is mounted on a pivot bar G and the block E may be adjustably held in place by means of a threaded bolt H passing down through a slot I in an extension J of the block E and threaded in the bottom of the last. Mounted in the openings in blocks C and E and extending between the two parts of the last is a bar K. Set astride said bar K is an inverted U-shaped coupling L. The two parts of the last or the blocks in which the bar K is mounted are connected by toggle links M on one or both sides thereof, the opposite ends being pivotally secured in the heel part and forepart respectively and the adjacent ends being pivotally secured to the coupling L. A threaded post N passes through a threaded opening in the top of the coupling and is stepped in the top of the bar and has a wrench receiving terminal O, whereby the turning of post N causes the coupling to rise or fall and the toggle links to contract or expand according as the post is turned.

The forepart of the last is divided longi-

tudinally and each part provided with one or more laterally extending holes P in which are mounted sustaining bars Q which extend across the line of division and serve to keep the two parts in proper vertical alinement. In the forepart of the last is mounted an expanding device comprising toggle links R provided at the inner extremity with holes S through which project vertical posts T set in the bottom of the last, one on each side thereof. The toggle links comprise two pairs which are connected by couplings U and W respectively. The couplings are provided with an operative post V terminating in a wrench receiving terminal V'. The part X of post V on which the coupling W' is mounted is threaded in one direction and the part X' on which the coupling U' is mounted is threaded in the opposite direction.

The operation of my improved repair last is as follows: To insert the last in the shoe, it is brought into the smallest compass, both longitudinally and laterally and then inserted in the shoe. The wrench is then applied to the vertical post N, the turning of which causes the U-shaped coupling to descend over the bar K carrying with it the adjacent ends of the toggle links, thus forcing the two parts of the last apart until the shoe is filled longitudinally. The wrench is then applied to the post of the expanding device and turned until the forepart is expanded to completely fill the shoe laterally. To remove the last from the shoe the operation is reversed, contracting the last both longitudinally and laterally.

The advantages of my improved last are simplicity of construction and operation, durability and adjustability, whereby the last is caused to fit the shoe both longitudinally and laterally.

Having thus described my invention and its use, I claim:

In a repair last, a toe part and heel part, a block mounted in the heel part and provided with a longitudinally positioned bar receiving opening, a block mounted in the

forepart and provided with a similar longitudinally positioned bar receiving opening, a bar slidably mounted in said blocks, a U-shaped coupling set astride said bar and vertically movable relative to and in contact with said bar, toggle links having their remote ends pivotally mounted in the heel part and toe part respectively and their ad-

jacent ends pivotally attached to said U-shaped coupling, and means for imparting vertical movement to said coupling.

DANIEL ROUNDS.
